UNITED STATES PATENT OFFICE.

MICHAEL J. MILMOE, OF CHICAGO, ILLINOIS, ASSIGNOR TO F. B. REDINGTON COMPANY, OF CHICAGO, ILLINOIS, A CORPORATION OF ILLINOIS.

CARTON-OPENING DEVICE.

1,218,683.

Specification of Letters Patent.

Patented Mar. 13, 1917.

Application filed March 4, 1916. Serial No. 82,074.

To all whom it may concern:

Be it known that I, MICHAEL J. MILMOE, citizen of the United States, residing at Chicago, in the county of Cook and State of Illinois, have invented certain new and useful Improvements in Carton-Opening Devices, of which the following is a specification.

This invention relates to machines for opening cartons usually made of stiff paper or cardboard and which are supplied to the trade in flattened form. When it is desired to fill such cartons with merchandise, the carton must be first opened and squared preparatory to the placing of the merchandise therein. In my prior Patent No. 1,177,719, April 4, 1916, is shown a machine for opening and filling such cartons, and the present invention relates particularly to a blade or finger to be used in connection with this and similar machines. The invention is exemplified in the combination and arrangement of parts shown in the accompanying drawing and described in the following specification, and it is more particularly pointed out in the appended claims.

In the drawing,—

Figure 1 is fragmentary plan view of a portion of a carton opening and filling machine showing the present invention in its relation to the coöperating parts of the machine;

Fig. 2 is a fragmentary side elevational view showing various stages of the operation of the carton opener blade;

Fig. 3 is a detail view showing the position of the point of the blade as it enters a closed carton;

Fig. 4 and Fig. 5 are plan and elevational views respectively of a slightly modified form of opener blade;

Fig. 6 is a transverse sectional view of an opened carton showing in section the form of blade illustrated in Figs. 4 and 5.

The present invention contemplates the opening of a flattened carton by first inserting a blade between the sides thereof and then operating the blade in conjunction with a relatively fixed stop or seat to complete the opening of the carton. A blade or finger for this purpose is shown at 10 in Figs. 1 to

3 inclusive of the drawing. This blade is carried by an arm 11, to which it is secured by means of screws 11'. The arm 11 is pivotally mounted on a rod 12 on which it is free to rotate, but the arm is constrained to move longitudinally with the rod 12 by means of a collar 13 rigidly secured to the rod, and the arm forms part of a rectangular framework made up of pivoted levers 14, a longitudinal bar 15 and the cylindrical rod 16. The entire rectangular framework is moved longitudinally with the rod 12 by means of a spur gear 17 and a rack 18. A link 19 has one end thereof pivotally secured to the bar 16 in such a manner that the bar 16 is free to slide longitudinally relative to the link. Pivotal movement is imparted to the rectangular framework and the arm 11 about the rod 12 by means of the link 19, which is operated by cam mechanism forming no part of the present invention. By this mechanism, the opener blade 10 may be moved longitudinally to cause it to enter between the sides of a closed carton, and may also be swung transversely to the axis thereof to move a carton laterally.

The flattened cartons are held in a magazine, the lower portion of which is shown at 20 in Fig. 2. The sides of this magazine are provided with supports or ledges 21 upon which the edges of the flattened cartons rest. The cartons to be opened are provided with end flaps, shown at 22 in Fig. 3. In opening a carton, the opener blade is first swung upwardly until it contacts with the lower side of one of these end flaps, and is then moved axially to cause the pointed end 23 thereof to enter between the sides of the carton, as shown in Fig. 3. During this entering action, the sides of the carton are forced apart for a slight distance and assume the position indicated in broken lines in Fig. 2. The arm 11 is then moved about its pivotal support to swing the carton through the various positions illustrated in Fig. 2, until the edges of the carton that were originally supported on the ledges 21 strike the walls of a receiving stop or seat. This seat is provided with a base member 24 and an upright member 25, preferably at approximately right angles to one another. As the arm 10

continues its downward movement, it draws the carton into the angle formed by the parts 24 and 25 and thus forces the carton to assume a rectangular position.

It should be noted that the finger 10 is considerably thickened in a direction transverse to the direction of movement of the operator during its rotation about the rod 12. This shape of the opener blade provides what are, in effect, strengthening ribs at the opposite sides thereof running longitudinally of the blade. The blade itself is necessarily comparatively long and slender, and it is therefore necessary to provide these strengthening portions to prevent the blade from bending or breaking in operation. It should also be noticed that the sides of the blade which enter into the corner of the carton receiving seat meet at such an angle with one another that they approximately fill the portion of this corner adjacent the vertex of the angle thereof.

In the modified form of opener blade shown in Figs. 4, 5 and 6, the blade is made approximately triangular in section. This is in effect the same blade as that shown in Fig. 2, but with the upper half of the blade removed, leaving only the lower strengthening rib,—that is, the rib which forms the angular portion for entering the corner of the carton receiving seat. The blade is also widened somewhat and the sides are made straight, with the exception that the corners are rounded. This form of blade gives a chisel or knife edge for entering between the sides of the carton, as indicated at 26 in Figs. 4 and 5. The lower edge of the blade is beveled to form the opening edge 26, and the top of the blade is also beveled slightly, as indicated in Fig. 5.

By this construction, I have provided an opener blade which may be forced between the sides of a carton to partially open the carton, and which is of sufficient strength to withstand repeated lateral movements for forcing the partially opened cartons laterally into position on the receiving seats. The particular shape of opener blade or finger comprised in the present invention is found to be especially efficient for the purpose for which it is designed, and capable of meeting the exacting conditions imposed upon such a blade where thousands of cartons are to be opened in rapid succession and where this operation is repeated day after day.

I claim:

1. In combination, a blade for opening flattened cartons, a carton seat, and mechanism for operating said blade to position cartons on said seat, said blade being thickened in a direction transverse to the direction of movement thereof.

2. In combination, a blade for opening flattened cartons, means for moving said

blade transversely to the longitudinal axis thereof to transport cartons, and a strengthening portion on said blade to prevent bending or breaking thereof.

3. In combination, a blade for opening flattened cartons, means for imparting a transverse movement to said blade to transport cartons, and a strengthening rib extending longitudinally of said blade to prevent bending or breaking thereof.

4. In combination, a blade for opening flattened cartons, means for imparting a transverse movement to said blade to transport cartons, an angular seat for receiving cartons so transported, and an angular rib extending longitudinally of said blade and adapted to fit into the apex of the angle formed by said seat.

5. In carton opening mechanism, an angular seat for receiving cartons, and a blade for moving cartons into said seat, said blade being shaped in cross section to approximately fill the portion of said seat adjacent the vertex of the angle thereof.

6. In combination, a blade for opening flattened cartons, a carton seat, means for operating said blade to position said carton in said seat, said blade being thickened transversely thereof to withstand the strains imposed thereon by said positioning operation.

7. In combination, a carton opener blade, means for moving said blade longitudinally to cause said blade to enter a carton, and means for moving said blade transversely to position said carton, said blade being thickened in a direction transverse to said positioning movement to strengthen said blade.

8. In combination, a carton opener blade, means for moving said blade into a carton to be opened, and means for operating said blade while within said carton to complete the opening thereof, said blade being thickened transversely to cause said blade to withstand said opening movements.

9. In combination, a carton receiving seat, a carton opening blade, means for moving said blade longitudinally to cause said blade to enter a carton, and means for operating said blade while within said carton to open and position said carton in said receiving seat, said blade being thickened transversely thereof relative to said opening and seating movement.

10. In combination, a carton opener blade, an angular seat for receiving cartons, and means for operating said blade to position cartons in said seat, said blade being shaped to fit the angle of said seat.

11. In combination, an angular carton receiving seat, and a blade for positioning cartons in said seat, said blade being approximately triangular in cross section.

12. In combination, a carton receiving seat having two walls at approximately right

angles to one another, and a blade for positioning cartons in said seat, said blade having two sides thereof at approximately right angles with one another and arranged to fit within the angle of said seat.

In testimony whereof I have signed my name to this specification, in the presence of

two subscribing witnesses, on this 2 day of March, A. D. 1916.

MICHAEL J. MILMOE.
